UNITED STATES PATENT OFFICE.

FRANCIS H. RICHARDS, OF SPRINGFIELD, MASS., ASSIGNOR TO THE AMERICAN BUTTON FASTENER COMPANY, OF NEW BRITAIN, CONN.

MECHANISM FOR FEEDING BUTTON-FASTENERS.

SPECIFICATION forming part of Letters Patent No. 322,971, dated July 28, 1885.

Application filed December 26, 1884. (No model.)

To all whom it may concern:

Be it known that I, FRANCIS H. RICHARDS, a citizen of the United States, residing at Springfield, in the county of Hampden and State of Massachusetts, have invented a new and useful Improvement in Button-Fastener-Feeding Machines, of which the following is a specification, reference being had to the accompanying drawings, in which—

10. Figure 1 is a plan view of a machine embodying my invention. Fig. 2 is an elevation of the front side of the same, drawn in projection to Fig. 1. Fig. 3 is an elevation of the end at the left hand in Fig. 2. Fig. 4 is a 15 partial section on line X X, Fig. 2. Fig. 5 is a vertical section through the carrier-wheel on line Y Y, Fig. 3. Fig. 6 is a figure used for illustrating the principle on which the machine is constructed. Fig. 7 is an enlarged 20 view of a part of Fig. 4.

Similar reference-characters refer to similar parts throughout the views.

This invention relates to improvements in machinery for feeding that kind of button-fasteners known in market as "Kempshall's One-Prong Button-Fasteners" from a hopper into a fastener-receiving channel or magazine.

The object of my invention is to furnish a 30 machine adapted to automatically feed said button-fasteners, or others substantially similar, into the said channel so they will all rest therein in the same position.

To this end the invention consists in certain 35 combinations of mechanism, which will first be described in connection with the drawings, and afterward particularly pointed out in the claims.

The principle on which the machine is constructed is substantially this: An apron or platform having a slot or channel, 10, across it is placed in about a horizontal position, A, Fig. 6, and a charge consisting of several of the button-fasteners is taken from a place of 40 supply and delivered onto said apron by means of any convenient elevator apparatus. Having received its charge, the apron is then gradually tipped, as shown by dotted lines at A², or carried and tipped to about the position shown at A⁴, A³ being an intermediate 45 position, when those fasteners not having their

prongs in the channel will slide off and be returned into the place of supply, which result may be facilitated and accelerated by means of a slight shaking of said platform by a device specially provided therefor, or by the natural vibration of the machinery.

A magazine having a groove adapted to receive the fasteners is so placed that when said apron reaches position A⁴ the channel thereof 55 will coincide with the entrance to said magazine, into the groove of which a plunger then drives any fasteners remaining in said channel. After this operation is completed the channelled apron is conveyed to its former 60 position to receive another charge of the fasteners, to be disposed of as before.

It will be obvious on examining Fig. 6 that the apron may be carried in either a vertical or a circuitous route, as shown, and that 65 if carried in the latter it may be returned to its position at A either by continuing or by reversing its motion.

In the machine herein described this principle has been embodied in an operative mechanism in which the apron is moved in a circuit, which circuit is a circular one, and has a series of the said aprons or platforms moving therein in regular succession. For delivering the charges of fasteners onto the platforms I prefer a bucket-conveyer adapted to take the said fasteners out of a hopper or receptacle into which they are thrown in a mass.

In the drawings, B designates the base of the frame-work of the machine. On this base 80 there is erected the principal upright, D, a bucket-wheel bearing, C, and the post E. The upright D has formed therein a bearing for apron-wheel F, which is held in said bearing by cap 2, secured by screws 3. Said upright 85 is also provided with side extensions, which form hopper H, and it is mortised at 4, Figs. 4 and 5, to admit of the passage of the conveyer, and at 5, Fig. 4, the pawl which turns the apron-wheel. This wheel consists of the 90 rim, with which the reference-letter F is connected, and a series of spokes, 6, projecting inwardly from said rim and each carrying one-half of two adjacent slotted aprons of the kind shown in Fig. 6, the extent of one of said 95 aprons being indicated by dotted lines 7 and 8, Fig. 3. By combining a series of such slotted

aprons into a wheel, as shown, there is formed a series of aprons, 9, each composed of the opposite halves of two such as shown in Fig. 6, the slots 10 being now between rather than in them. Thus we have a series of aprons and slots, of which the slots may be in or between the aprons according to the method of construction adopted, and which in either case operates on precisely the same principle.

10 In order to increase the efficiency of the apron-wheel, depressions 11 and 12, Fig. 6, of about the form shown, are formed in the aprons on either side of the slots, the effect of these being to so guide the fasteners in their passage over the slots during the tipping of said aprons that their prongs will more frequently fall through, and with the heads in the right direction, as shown at 13, Fig. 6. Notwithstanding this, however, some of the fasteners 20 may be carried up with their heads turned in the wrong direction, as at 14, position A⁴, the long end of the heads reaching beyond the narrow depression 12. To facilitate the dislodgment of these, the upper side of the slot 25 is inclined, as at 15, so that the weight of the head will overbalance that of the prong, and thus cause the fastener to fall out. The opposite edge of depression 11 is beveled off to about the angle shown at 16, so that any fastener lying flatwise, as at 17, Figs. 4 and 5, over the slots will slide off before said slots reach position A⁴.

It will be understood that if a fastener while in a vertical plane enters a slot, it immediately falls through, as shown at 18, Fig. 5, and is returned to the mass in the hopper.

S designates the driving-shaft, which runs in bearings formed in upright D and post E, and which is provided with pulley P, whereby 40 it is driven with cam M, which acts through pawl 20 against notches 19 of the apron-wheel for intermittently rotating said wheel, and with cam N, which is herein described. Cam M is preferably so formed as to impart an irregular 45 upward movement to said pawl for the purpose of shaking or jarring the apron-wheel while it is turning, as hereinbefore mentioned. The said pawl is preferably furnished with a roller, 21, bearing against said cam. It has 50 also a pin, 22, which is acted upon by spring 23 for the purpose of keeping the point of said pawl against the apron-wheel notches.

The construction of this apron-wheel feeding mechanism is such that each revolution of 55 the driving-shaft will bring one of the slots 10 of said wheel into line with the fastener-receiving channel L, which is rigidly supported on the frame in any convenient way. As shown in the drawings, it is secured by a 60 screw, 25, to an ear, 26, projecting from hopper H, this hopper being considered a part of the frame. At the end nearest the apron-wheel the channel L is about radial to said wheel, but in passing therefrom takes a spiral 65 course until it reaches a vertical position, as at 64, Fig. 2.

On the opposite side of the apron-wheel

from channel L the plunger G is supported by and adapted to have a longitudinally-reciprocating motion in bearings formed in the hopper-wall and post E. Said plunger is operated by cam N, acting on roll 28 of lever 29, which lever is pivoted to the frame at 30, and connected to the plunger at 31 in the ordinary way of making such connections. 75

The construction and arrangement of the parts are such that cam N acts to throw the plunger away from the apron-wheel toward the right hand in Figs. 1 and 2, and a spring, 33, connected to said lever at 34 and to the frame 80 at 35, is provided for driving the plunger toward said wheel whenever the cam will permit it so to do.

Plunger G is provided with a wing, 40, which serves as a spline to prevent it from turning 85 in its bearings, and which when, in the operation of the machine, a slot, 10, is in line with channel L, acts to drive any fasteners properly placed in said slot out of the same into said channel, this being accomplished by the power 90 of spring 33 aforesaid. The working end of said plunger, is preferably provided with a plate, 41, formed to correspond with depressions 11 and 12, as at 42, Fig. 7. This plate should have a projection, 43, for pushing 95 around the heads of any fasteners which may reach position 14, Fig. 7, with their heads in the wrong direction, and also a finger, 44, for dislodging any bunches of fasteners which may come up into range with it, as at 45, 100 Fig. 4.

For the purpose of supplying fasteners to the apron-wheel in suitable quantities and at proper intervals, an endless conveyer provided with suitable buckets is arranged to receive said fasteners from hopper and discharge them a bucketful at a time onto the lowest part of said apron-wheel, as shown in Figs. 4 and 5. This conveyer consists of a chambered wheel, W, the lower part of which coincides approximately with the hopper. Buckets 48 are placed within said chamber to receive the fasteners from the bottom of the hopper, as at 49, Fig. 5, and to elevate them to 50, where they will discharge onto the apron-wheel, as shown in said figure. The bucket-wheel may be made in two parts, held together by two screws, 51, to allow the placing of it in position surrounding the lower side of the apron-wheel. A part of the periphery of said bucket-wheel is fitted to bearing C, being held therein by cap 60, and revolved by belt 61 or equivalent means. 110 115 120

By comparing Figs. 3 and 6 it will be seen that the position of channel L in Fig. 3 corresponds with that of the apron at A⁴ in Fig. 6, and that each of the aprons composing the apron-wheel passes through successive points in its circuit which correspond to the successive positions A, A³, and A⁴; hence it is 125 obvious that said wheel may justly be considered as consisting of one or more slotted aprons, each of which, when a series is employed, 130 acts independently of the others.

The operation of my improved button-fastener-feeding machine will be readily understood from the drawings and the preceding description, being as follows: The machinery 5 being started up, a quantity of fasteners, substantially such as described, are thrown into the hopper H in a mass, which mass then slides down said hopper more or less into wheel W, the buckets of which take up charges 10 of the fasteners and dump them onto the lower part of the apron-wheel, substantially as in Figs. 4 and 5. From this point the fasteners are gradually carried forward into alignment with channel L, all but those properly 15 placed in slots 10 being shaken or pushed off or through said slots before they reach that point where those remaining are driven out by the plunger into the channel, these operations continuing until the mass is exhausted. 20 It will of course be understood that the cams are to be so timed as to operate in succession, the apron-wheel being at rest while the plunger performs its function, and vice versa.

Having thus described my invention, I 25 claim—

1. In a button-fastener-feeding machine, the combination of a slotted apron, means, substantially as described, for delivering button-fasteners onto said apron, means, substantially 30 as described, for tipping and bringing said apron into alignment with a fastener-receiving channel, a fastener-receiving channel, and a plunger for pushing fasteners out of the slot in said apron into said channel, all arranged to operate substantially as described. 35

2. In a button-fastener-feeding machine, the

combination of a series of slotted aprons arranged to travel in a circuit, means, substantially as described, for delivering button-fasteners onto the lower aprons of said series, 40 means, substantially as described, for moving forward said aprons in said circuit to successively bring each apron with its slot into alignment with a fastener-receiving channel, a fastener-receiving channel, and a plunger for pushing fasteners out of said slots into said channel, all arranged to operate substantially as described. 45

3. In a button-fastener-feeding machine, the combination of an apron-wheel having a series 50 of slotted aprons supported by inwardly-projecting spokes and suitable operating devices, substantially as described.

4. In a button-fastener-feeding machine, the combination of a slotted apron having de- 55 pressions 11 and 12 and suitable operating devices, substantially as and for the purpose described.

5. In a button-fastener-feeding machine, the combination of an apron-wheel having platforms 60 9, which are provided with depressions 11 and 12, and a plunger provided with projection 43, and suitable operative means, substantially as and for the purpose described.

6. The combination of the apron-wheel F 65 and its slotted aprons, hopper H, and bucket-wheel W, and suitable operating means, substantially as and for the purpose described.

FRANCIS H. RICHARDS.
